The ornamental design for a hair clip, as shown and described.

DESCRIPTION

FIG. 1 is a front perspective view of a hair clip;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is an angled top view thereof;

FIG. 8 is another angled top view thereof; and,

FIG. 9 is yet another angled top view thereof.

The broken lines in the drawing are for illustrative purposes only and form no part of the claimed design.
